UNITED STATES PATENT OFFICE

169,358

BEVERAGE BREWING DEVICE

Robert D. Budlong, Skokie, Ill., assignor to Cory Corporation, Chicago, Ill., a corporation of Delaware

Application January 19, 1953, Serial No. 23,194

Term of patent 7 years

(CL. D44—26)

To all whom it may concern:

Be it known that I, Robert D. Budlong, a citizen of the United States, residing at Skokie, in the county of Cook, and State of Illinois, have invented a new, original, and ornamental Design for a Beverage Brewing Device, of which the following is a specification, reference being had to the accompanying drawing, forming part hereof.

In the drawing:

Fig. 1 is a side elevational view of a beverage brewing device embodying my new design.

Fig. 2 is an elevational view taken from the left in Fig. 1.

Fig. 3 is a top plan view.

I claim:

The ornamental design for a beverage brewing device, as shown.

ROBERT D. BUDLONG.
